(57) **CLAIM**

The ornamental design for a face mask connector cinch, as shown and described.

DESCRIPTION

FIG. 1 is a rear perspective view of a face mask connector cinch showing our new design;

FIG. 2 is a left side elevational view thereof, the right side being a mirror image;

FIG. 3 is a top plan view thereof, the bottom view being a mirror image;

FIG. 4 is a front elevational view thereof;

FIG. 5 is a rear elevational view thereof; and,

FIG. 6 is a perspective view thereof, showing the cinch on a face mask.

The broken line drawings of the face mask are for illustrative environmental purposes only and form no part of the claimed design.
